INVENTOR:

Samuel Lustig

BY Partners & Co. ATTY'S:

UNITED STATES PATENT OFFICE.

SAMUEL LUSTIG, OF PATERSON, NEW JERSEY.

DESIGN FOR A COURT-PLASTER BOX.

SPECIFICATION forming part of Design No. 26,578, dated February 2, 1897.

Application filed December 3, 1896. Serial No. 614,361. Term of patent 3½ years.

To all whom it may concern:

Be it known that I, SAMUEL LUSTIG, a citizen of the United States, residing in Paterson, county of Passaic, and State of New Jersey, have invented and produced a new and original Design for Court-Plaster Boxes, of which the following is a specification, reference being had to the accompanying drawings, and to letters of reference marked thereon, which form a part of this specification.

My invention has reference to a new design for court-plaster boxes and is illustrated in the accompanying drawings, in which—

Figure 1 is a top plan view of a court-plaster box, showing my design; Fig. 2, a top plan view of the same, the lid or cover being removed; and Fig. 3, a sectional view on the line xx of Fig. 1.

The leading features of my design consist in raised stars placed in the corners of the lid or cover and in the depressions arranged in the bottom of the box and radially diverging from and surrounding a central circular depression.

In the drawings, a denotes the lid, having 25 the sides b b and c c arranged at right angles to each other and connected by the curved lines d d . In each of the corners of said lid is arranged a star of suitable shape, preferably as illustrated.

The bottom of the box is designated by a' , having the sides b' b' and c' c' , connected by the curved lines d' d' . The central portion of said bottom is depressed, as at f , and in its corners are arranged the depressions g , g' , 35 g^2 , and g^3 , diverging substantially radially from the central depression.

What I claim is—

The design for a court-plaster box, substantially as shown and described.

In testimony that I claim the foregoing I have hereunto set my hand this 24th day of November, 1896.

SAMUEL LUSTIG.
